MULTIPLE-HEADED WINDING MACHINE

Hermann Grein, Remscheid-Lenne, and Werner Zander, Wuppertal-Eberfeld, Germany, assignors to Barmer Maschinenfabrik Aktiengesellschaft, Wuppertal-Oberbarmen, Germany

Application January 28, 1957, Serial No. 636,629

Claims priority, application Germany February 1, 1956

9 Claims. (Cl. 242—35.5)

This invention, in general, relates to multiple-head winding machines and, in particular, to space-saving arrangements of the bobbin heads on the machine frames.

With the increasing rate of production in the manufacture of synthetic thread, the space problem becomes especially important in those cases in which the body of thread, which is first formed on the spinning machine, cannot be used without further processing of the thread and must be brought into the form of winding suited to the particular application by machines especially designed for this purpose in a separate operation.

In the known multiple-headed winding machines, the bobbin heads, which each consist of a driving gear arrangement and the bobbin proper, are normally situated one behind the other along the length of the machine—either in a single row with bobbins extending the same direction and projecting at a right angle on one side of the machine, or else in two such rows along the length of the machine, running next to one another with the bobbins in each case extending the same direction, projecting at a right angle on the one side and on the other side of the machine, or even in several such double rows in tiers, one above the other, in which arrangement the bobbin heads are driven either in common, in groups of several bobbin heads or singly.

A disadvantage in the tending of such machines with double rows of bobbin heads closely crowded one behind the other is that these rows, in their multiplicity of spindles and winding members facing in the same direction, obscure the view and thereby make checking difficult, and, also, as a result of the crowded construction, access is difficult in case of failures in operation.

In accordance with the invention, an object thereof is to accommodate as many bobbin heads as possible in a small space. The invention provides better view and improved accessibility of the individual bobbins and of the gear sets without sacrificing the compact design which is recognized as necessary. This is accomplished in a multiple-headed bobbin machine, according to the invention, with bobbin heads situated in one or more tiers, by having the gear sets of the bobbins along the length of the machine in one row or in several such rows arranged in tiers, one above the other, and, in some cases, within a row or in tiers alternately opposed to one another, so that the bobbins, as has hitherto been usual only in double-row winding machines, project at both sides of the machine.

In the further development of the idea of the invention, the arrangement may be made in such a way that the bobbin heads or their gear sets lie at an angle to the length of the machine. In this manner the overall view and the accessibility of the individual bobbins and of the gear sets is considerably improved, with a specially good utilization of space. Because each bobbin projects freely for a certain distance from the contour of the machine frame with respect to the neighboring bobbins, and accordingly, is accessible not only from the front but also from the side, it is possible to move the

bobbin heads or their gear sets closer together and accomplish further economies of space.

With this arrangement carried out at an angle to the length of the machine, the gear sets can, in turn, be arranged in succession in a row or in several rows in tiers one above the other, and, in fact, within a row or in tiers they may be arranged in opposition. The size of the angle is governed essentially by the relation of the length of the gear set to the bobbin. At a relationship of 1:1 it will amount, advantageously, to 45° with respect to the longitudinal direction of the machine frame. If the bobbin is smaller in relation to the gear set, then the angle is larger; if, on the other hand, the bobbin is larger, then the angle should be made smaller.

According to the foregoing, the most diverse possibilities are yielded for an advantageous, clear-view and space-saving arrangement and grouping of the bobbin locations. Thus, for example, it is even possible to arrange the gear sets lying at an arbitrary angle to the length of the machine in pairs, staggered in relation to their bobbin locations, or to arrange them in several such rows in tiers one over the other, in such a way that then the bobbin locations protrude from the machine alternately to the one side and to the other. In this manner a further saving of space can be achieved.

Finally, with the compact design of bobbin heads lying close together, the gear sets can be accommodated in each case in groups or in one common housing, so that the driving and control mechanisms may be grouped together and, furthermore, there is a saving in the weight of the machine.

In the drawing, several examples of execution are schematically represented.

Fig. 1 shows a multiple-bobbin head winding machine with gear sets mounted in a successive row, arranged in alternating opposition;

Fig. 2 shows a multiple-bobbin head, tiered winding machine with several gear sets arranged in several rows, one above the other, in opposition in a checkerboard pattern;

Fig. 3 shows a multiple-bobbin head, tiered winding machine with gear sets arranged in several individual rows one above the other, in opposition by tiers;

Figures 4 through 6 are the schematic representation of Figures 1 through 3 in plan;

Fig. 7 shows in plan a multiple-bobbin head winding machine similar to that of Fig. 1, in which the gear sets are arranged at an angle to the length of the machine;

Fig. 8 shows in plan a multiple-bobbin head, tiered winding machine similar to that of Fig. 2, in which the gear sets are arranged at an angle to the length of the machine;

Fig. 9 shows in plan a multiple-bobbin head, tiered winding machine, similar to that of Fig. 3, in which the gear sets are arranged at an angle to the length of the machine;

Fig. 10 shows a multiple-bobbin head winding machine in which two rows, situated one above the other similar to Fig. 9, are united in one row, so that a herring-bone grouping of the gear sets, arranged in staggered pairs, results; and,

Fig. 11 shows a multiple-bobbin head winding machine, in which the superimposed rows similar to Fig. 8 are combined in one row and the gear sets, likewise arranged in staggered pairs, are enclosed in a common housing.

Broadly speaking, the multiple-bobbin head winding machines of this invention have adjacent bobbins in at least one, or in some cases both, of the horizontal and vertical directions alternately projecting on opposite sides of the longitudinal axis of the machine frame. In certain embodiments, the respective axes of the bobbin heads

are at an acute angle with respect to the longitudinal axis of the machine frames.

Referring now to the drawings, the bobbin heads are mounted on machine frame 20 and consist of the gear sets 22 and the bobbins proper 24 and 24'. The numeral 24 indicates the bobbins of the upper tier of the machine and 24' those of a lower tier or tiers. The original thread-winding bodies 26 supply the thread to be wound through gate brakes 28, which are thread-tensioning devices, and reciprocating traveller mechanisms 30, which distribute the thread in even layers over the bobbins 24 and are driven by gear connections with the gear sets 22 of the bobbin heads in a manner well known in the art. Figures 1, 4 and 7 show the arrangement of multiple-headed bobbin machines with gear sets mounted in succession in a row, alternately opposed. Figures 2, 5 and 8 show the mounting of several such individual rows in tiers one above the other. Figures 3, 6 and 9 show the arrangement of gear sets with the bobbin locations lying in the same direction within a row, but opposed by tiers.

In Fig. 9, the gear sets 22 are mounted not only at an angle to the length of the machine, but also at an angle to one another; it is also possible to mount the gear sets at an angle to the length of the machine only, so that the sets in rows one above the other have the same axial direction, but have the bobbin locations opposed. In the last case, the employment of identical bobbin heads is possible, whereas the bobbin heads of the opposite direction, as, for example, according to Figure 9, require a mirror-image construction.

Another arrangement of the multiple bobbin heads is illustrated in Fig. 10, wherein the staggering of the bobbin heads on the machine frame 20 is achieved by placing the rear edge of each gear set 22 in contact with a side of the gear set immediately preceding to provide a herringbone pattern of the gear sets on the machine frame. The bobbin heads are, thus, arranged in staggered pairs, one bobbin head of each pair extending from one side of the frame and the other from the other side of the frame, to form a row composed of two horizontal lines of bobbin drive means extending along the longitudinal axis of the frame. One line is composed of parallel bobbin gear sets extending from one side of the frame 20 and projecting toward one end of the frame to form an acute angle with the longitudinal axis of the frame. The other line of parallel bobbin gear sets extend from the opposite side of the frame and project toward the same end of the frame as the gear sets in the first-mentioned line to also form an acute angle with the longitudinal axis of the frame. This arrangement provides a herringbone arrangement of the gear sets 22 and associated bobbins 24, whereby the bobbins of longitudinally adjacent gear sets 22 alternately project from opposite sides of the frame 20.

In the examples represented in the figures, all the bobbin heads are equipped with individual drive. The bobbin heads, may, however, be powered in groups or all in common.

The examples of arrangements represented offer the possibility of moving the bobbin heads with their gear sets so close together that each individual bobbin head no longer represents an independent set and several or all of the bobbin heads can be accommodated in over-all housings with drive by groups or over-all drive.

The employment of such novel groupings of bobbin heads is not restricted only to the various needs of winding operations, but may be employed to similar advantage for other purposes as well, as, for example, for the production and after-treatment of rayon threads in a continuous operation.

The invention is hereby claimed as follows:

1. A multiple-bobbin head winding machine comprising a frame, a plurality of bobbins and associated drive means mounted in side by side relationship in horizontal

rows on said frame in a plurality of vertically superposed tiers, a plurality of thread supply windings mounted on said frame with a winding positioned immediately below each bobbin for supplying thread thereto, the bobbins being arranged on said frame such that the bobbins driven by adjacent drive means in at least one of the horizontal or vertical directions project from opposite sides of the longitudinal axis of the frame.

2. The machine of claim 1 wherein the machine consists of tiers of horizontal rows of individual bobbin drive means with the bobbins of adjacent drive means in the horizontal direction alternately projecting from opposite sides of the frame.

3. The machine of claim 1 wherein the bobbins of adjacent drive means in both the vertical and horizontal directions project from opposite sides of the frame and the thread supplies for at least some of the bobbins are positioned between the bobbins and associated drive means in the next lower tier.

4. The machine of claim 1 wherein the bobbins in a given tier project from the same side of the frame, the bobbins in the next adjacent tiers projecting from the opposite side of said frame.

5. A multiple-bobbin head winding machine comprising a frame, a plurality of bobbin drive means mounted on said frame in side by side relationship in horizontal rows in a plurality of vertically superposed tiers extending along the longitudinal axis of the frame, the bobbin drive means being mounted on said frame at an acute angle to the longitudinal axis thereof, each drive means having a bobbin associated therewith with the bobbins projecting laterally with respect to the longitudinal axis of the frame at a corresponding angle to the acute angle of said bobbin drive means, a plurality of thread supply windings mounted on said frame with a thread-winding positioned immediately below each of said bobbins for supplying thread thereto, the bobbin drive means being arranged so that the associated bobbins of adjacent drive means project alternately, in at least one of the horizontal or vertical directions, on opposite sides of the longitudinal axis of the frame.

6. The machine of claim 5 wherein the machine consists of tiers of horizontal rows of bobbin drive means with the bobbins of adjacent drive means in the horizontal direction alternately projecting from opposite sides of the frame.

7. The machine of claim 5 wherein the bobbins of adjacent drive means in both the vertical and horizontal directions project from opposite sides of the frame and the thread supplies for at least some of the bobbins are positioned between the bobbins and associated drive means in the next lower tier.

8. The machine of claim 5 wherein the bobbins in a given tier project from the same side of the frame, the bobbins in the next adjacent tiers projecting from the opposite side of said frame.

9. The machine of claim 1 wherein the bobbin projects axially from each drive means, a plurality of thread supply windings mounted on said frame with a thread-winding positioned immediately below each of said bobbins for supplying thread thereto, the drive means being positioned on said frame in staggered pairs to form a row composed of two horizontal lines of bobbin drive means extending along the longitudinal axis of the frame, one line being composed of parallel bobbin drive means

extending from one side of said frame and projecting toward one end of said frame to form an acute angle with the longitudinal axis of said frame and the other line being composed of parallel bobbin drive means extending from the opposite side of said frame and projecting toward the same end of said frame as the bobbin drive means in said first-mentioned line and also forming an acute angle with the longitudinal axis of said frame, to thereby provide an arrangement of said bobbin drive means in a herringbone pattern, said machine having a

plurality of said rows in the form of vertically superposed tiers, whereby the bobbins of longitudinally adjacent drive mechanisms alternately project from opposite sides of said frame.
